UNITED STATES PATENT OFFICE.

AXEL TEODOR NYGREN, OF STOCKHOLM, SWEDEN, ASSIGNOR TO ANDERS VICTOR CARLSON AND PETTER JOHAN ALFRED NYGREN, OF SAME PLACE.

PORTABLE SCAFFOLD.

SPECIFICATION forming part of Letters Patent No. 447,898, dated March 10, 1891.

Application filed November 19, 1889. Serial No. 330,934. (No model.) Patented in Sweden August 8, 1889, No. 1,928, and in Germany September 20, 1889, No. 48,608.

To all whom it may concern:

Be it known that I, AXEL TEODOR NYGREN, a subject of the King of Sweden, residing at Stockholm, Sweden, have invented certain Improvements in Portable Scaffolds, (for which a patent has been granted in Sweden, No. 1,928, dated August 8, 1889, and in Germany, No. 48,608, dated September 20, 1889,) of which the following is a specification.

My invention relates to a scaffold for exterior work on buildings, which may be moved sidewise or laterally, so that the workman may by means thereof be able to transfer himself from one part of the face of the building to another as the work progresses. This scaffold forms a substitute for a stationary scaffold such as is usually employed for such work.

In the accompanying drawings, illustrative of my invention, Figure 1 is a perspective view of a scaffold embodying my improvements mounted on a building. Figs. 1^a and 1^b are detail views, on a larger scale, of parts of the winding mechanism on the chair, the former being a side view of same and the latter an end view. Fig. 2 is a detail view that will be hereinafter described. Fig. 3 is a side view of the bracket, showing its adaptation to a double-track rail for the carriage from which the chair is suspended.

The scaffold consists, substantially as shown in Fig. 1, of a hoisting-chair A, the bearing-ropes of which run on four pulleys B, fixed to a laterally-moving carriage, which, by means of two track-wheels C, runs upon a rail D. The rail D extends along the whole front of the building and is supported by brackets fixed to the building in such a manner that its upper edge is free along the whole length, so that the hoisting-chair may be moved laterally as far as the length of the rail. These brackets, of which only one is shown in the drawings, are so placed as to be fastened to the roof. The bracket comprises a bar a, secured adjustably at its upper end to a support b, secured to the roof Y, and near the eaves to a support c, which also rests on the roof. This bar a projects out over the cornice X of the house, where it is con-

nected adjustably to a bar a', which projects inward obliquely toward the house-wall. A tie-bar a² connects the bars a and a' together adjustably, the three bars forming a triangular truss or frame. A bent or angular suspender a³ is coupled at its upper end to the free end of the bar a', and has a stirrup a^x at its lower extremity to receive the rail D. A brace a⁴ connects the suspender a³ to the projecting extremity of the bar a. The connected bars forming the bracket are coupled together adjustably in order that the suspender a³ may hang vertically, whatever may be the angle of the roof, and this adjustability is attained by rows of holes in the respective bars and pins d, to couple the bars together, through the medium of said holes, as clearly shown.

Where the track-rail D is necessarily long, it may be made in sections and these sections be secured together by fastenings at the points where said rail rests in the stirrups a^x of the brackets.

The suspended chair is provided with a tackle or purchase, so that it may be moved vertically and sidewise, either simultaneously or otherwise. With the crank-shaft K both the shafts l are geared by means of bevel-wheels. On each of these shafts l are two drums m for the hoisting-ropes m', and two other rope-drums n and o, which, geared with the shafts l, serve to move the suspended chair laterally. On the latter rope-drums ropes q are wound, the ends whereof are secured to the respective ends of the rail D and supported or guided on guide-sheaves p. The proportion of the gearing between the rope-drums n and o and the drums m on shafts l is such that when the suspended chair is raised or lowered by turning the shaft K the rope q will be taken up or let out from the drums n and o to the proper extent. If the pinion r on shaft l be disconnected or disengaged, then the chair may be moved laterally by turning the respective drums n and o, so as to unwind one rope q from one drum and wind the other rope q on the other drum. If both the drums n and o be loose and one of them be connected by means of the pinion r and the shaft K be

- turned, the chair A will at the same time be moved laterally and raised or lowered. Two ratchet-wheels *s*, with pawls or detents *t*, prevent the chair from falling, and two fenders 5 *u*, provided with anti-friction rollers or the like at their ends, may, with the rollers, be pushed against the wall, so that the chair may not touch the wall, but will nevertheless be suspended firmly.
- 10 The shaft K may in lieu of a crank be provided with a wheel for turning it, or it may be rotated by means of screw-gearing. Where the building has a rounded corner, the rail D may be carried round this corner. At the 15 gables the rail must be supported by ropes fixed to suspenders similar to suspender *a*³, provided with a bent piece, so that the suspender-arms shall stand projecting out from the wall, and at the top be fixed to beams 20 passed through apertures in the gable or placed upon the roof, with the ends passing beyond the wall and fixed in a convenient manner to the roof.
- Fig. 2 shows an arrangement for adjusting 25 the chair sidewise horizontally while suspended. This is effected by winding up the slack of the rope left after raising or lowering the chair. This device consists of a hook-pawl *c*', engaging a ratchet-wheel *d*', fixed on 30 the shaft *l*, on which the rope-drums turn loosely. The hook-pawl *c*' prevents the drum from turning round because of the strain on the rope. At the opposite end of the rope-drum there is a boss or center *f*', which has 35 the form of a polygonal nut. If the rope is too long, the drum is turned a little by means of a wrench on this boss, so as to take up the slack or surplus. The hook-pawl has a spring to keep it in engagement, and said pawl prevents the drum from rotating backward. It is 40 evident that the drums *n* and *o*, provided with the above-described device, may likewise be mounted directly on the respective shafts *l*. When it is desired to move the chair laterally, 45 the drums will be turned by the aforesaid wrench and afterward locked by some suitable device. However, the wrench would preferably be fixed to the shaft as a crank, so that it could be used as a lever.
- 50 Fig. 3 shows how the carriage which supports the chair A may be mounted on two rails D instead of one, as seen in Fig. 1. This modification will require no special description. It is only necessary to modify the form of

the suspender *a*⁴, so that it has two stirrups 55 instead of one to support the respective rails.

I do not limit myself to the specific details of construction of the chair, as the construction shown may be modified somewhat without materially departing from the principles 60 of my invention.

Having thus described my invention, I claim—

1. In a portable scaffold, the combination, 65 with the rail or rails for supporting the carriage, of a bracket consisting of the bar *a*, which is supported on the roof and projects therefrom, the bar *a*', pivotally connected to the bar *a*, the tie-bar *a*², connected adjustably to the bars *a* and *a*', the three bars forming 70 a triangle, the suspender for the rail or rails, and the brace *a*⁴, connecting the bar *a* with said suspender, substantially as set forth.

2. In a portable scaffold, the combination, 75 with the rail D and the carriage mounted thereon and provided with supporting-pulleys and guide-pulleys, of the chair A, the rope-drums *m* *m* and their shafts mounted on said chair, the hoisting-ropes on said drums, which pass over the respective supporting- 80 pulleys on the carriage, the rope-drums *n* and *o* on the chair, geared to the shafts of the drums *m*, the ropes *q* on said drums, which pass over the respective guide-pulleys on the carriage and are secured to the respective 85 ends of the rail D, and the crank-shaft K, geared at its ends to the respective shafts *l* of the drums *m*, whereby all the drums are or may be rotated simultaneously, for the purpose specified. 90

3. In a portable scaffold, the combination, 95 with a support therefor, of the chair A, the four hoisting-rope drums *m*, mounted rotatively thereon, two at each end thereof, as described, the shafts of said drums, the hoisting-ropes adapted to be wound on said drums when the chair is hoisted, and the longitudinally-arranged crank-shaft K on said chair, said crank-shaft being geared at its ends with the transverse drum-shafts, substantially as 100 set forth.

In witness whereof I have hereunto signed my name in the presence of two subscribing witnesses.

AXEL TEODOR NYGREN.
